UNITED STATES PATENT OFFICE.

HARRY E. ASBURY, OF PHILADELPHIA, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

SAD-IRON.

No. 895,326.

Specification of Letters Patent.

Patented Aug. 4, 1908.

Application filed July 16, 1904. Serial No. 216,533.

To all whom it may concern:

Be it known that I, HARRY E. ASBURY, a citizen of the United States, residing in Philadelphia, Pennsylvania, have invented certain Improvements in Sad-Irons, of which the following is a specification.

The object of my invention is to provide a light and substantial cap for a detachable handle sad iron which will snugly fit the body portion of the iron and which will provide a substantial cross bar to which the handle can be attached. This object I attain in the following manner, reference being had to the accompanying drawing, in which:

15 Figure 1, is a plan view of my improved sad iron; Fig. 2, is a side view; Fig. 3, is a longitudinal sectional view of the cap on the line 3—3, Fig. 1; Fig. 4, is a transverse sectional view of the iron on the line 4—4, Fig. 20 1; and Fig. 5, is a transverse sectional view of the cap on the line 5—5, Fig. 1.

A is the body of the iron, which can be made in any suitable manner, but is preferably made as shown in the cross section, 25 Fig. 4, and is preferably pointed at each end, as shown in Fig. 1.

B is a cap, in the present instance made of sheet steel and pressed into shape, this cap has a flange b extending around its edge and 30 when the cap is in position this flange extends over the edge of the body A and snugly fits against the side walls of said body and relieves the securing screws c from lateral strains.

35 On each side of a central cross bar b' are openings b², b² for the reception of the latch of the handle which engages the cross bar b'. The bar b' is strengthened by turning down the metal, to form inturned flanges as shown 40 in Fig. 3, making in fact a hollow bar which is very strong, and in order to strengthen the cap at the opening I form a flange d at each side of each opening, as shown in Figs. 3 and 4.

45 At each side of the center of the cap are two longitudinal ribs e, e acting as guides for the handle and as these ribs are pressed up

from the plate forming the cap they materially strengthen the cap. Near each end of the cap is a pressed up cross rib f acting as a support for the handle and these ribs also 50 strengthen the cap. Tapered flanges g surround the screw holes in the present instance.

By this invention I am enabled to make a very light cap of sheet steel, which can be readily applied to the body of the iron and 55 which cannot be accidentally broken.

I claim

1. As a new article of manufacture, a pressed metal cap for sad irons having two openings separated by a central transverse 60 bar integral with the body of the cap, said bar having depending flanges, the flanges being bent towards each other at their lower ends to form a hollow member to be engaged by the catch of the handle of the sad iron, 65 substantially as described.

2. As a new article of manufacture, a pressed metal cap for a sad iron having an integral downwardly projecting flange extending around its edge arranged to fit over 70 the body of the iron and having two openings forming a central transverse bar with downwardly projecting flanges, said cap having two longitudinal ribs, one at each side of the cap, said ribs being pressed up from the 75 body of the cap and forming guides for a detachable handle, substantially as described.

3. As a new article of manufacture, a pressed metal cap for a sad iron having two openings forming a central transverse bar 80 with downwardly projecting flanges, and downwardly projecting flanges on each side of each opening connecting with the flanges of the bar, substantially as described.

In testimony whereof, I have signed my 85 name to this specification, in the presence of two subscribing witnesses.

HARRY E. ASBURY.
